UNITED STATES PATENT OFFICE.

WILLIAM KLOCHE, OF NEW YORK, N. Y., ASSIGNOR TO E. W. BLISS COMPANY, OF BROOKLYN, NEW YORK, A CORPORATION OF WEST VIRGINIA.

DRAWING PRESS.

Application filed June 5, 1920. Serial No. 386,839.

To all whom it may concern:

Be it known that I, WILLIAM KLOCHE, a citizen of the United States of America, residing in New York city, borough of

5 Queens, in the county of Queens and State of New York, have invented certain new and useful Improvements in Drawing Presses, of which the following is a specification.

This invention relates to improvements 10 in drawing presses, and aims to provide improvements therein.

The invention provides a novel blank-holder or die-carrying slide operating mechanism, of simple, durable and efficient 15 construction, and well adapted to transmit symmetrical pressure to such a slide.

The invention further provides a construction wherein the parts of the blank-holder or die-carrying slide operating mechanism may be arranged in close proximity 20 on the frame of the press, and also preferably in close association and proximity to the punch slide operating mechanism.

The invention further comprises a novel 25 combination, and sub-combinations, hereinafter more fully set forth, of parts constituting a drawing press.

Two embodiments of the invention are 30 illustrated in the accompanying drawings.

35 In said drawings, Figure 1 is a front or rear view, in elevation, of a drawing press according to one embodiment of the invention.

Figure 2 is a side view of the press shown 35 in Figure 1.

Figure 3 is a view similar to Figure 1, of a second embodiment of the invention.

Figure 4 is a view, in side elevation, of 40 the parts shown in Figure 3.

45 Referring to said drawings, numeral 1 designates a slide adapted to reciprocate to and from a bed 3, one of these parts being adapted to carry a blank-holder and the other part being adapted to carry a die.

50 Numeral 5 designates a punch slide, which may work either toward the bed or the blank-holder, depending upon the position of the die, but, as here shown, is preferably arranged to work through the slide 1.

55 The slide 1 conveniently reciprocates upon slideways or gibbs 7, on the side pieces 9 of the press frame, these side pieces being conveniently connected by an overhead intermediate piece 10.

60 Numeral 15 designates the mechanism for

operating the punch slide and numeral 17 designates the means for operating the blank holder slide.

The means for operating the punch slide conveniently comprises a crank shaft 18, 60 connected to the slide 5 through suitable connecting rods 19, and the crank shaft 18 preferably extends through the side pieces 9 of the press frame, and conveniently has, on its outer end or ends, a rotary driving part, as, for example, a wheel or gear 20. In the case of wide presses or heavy duty presses, it is preferable to provide driving parts 20 at each end of the crank shaft 18.

The blank-holder slide operating mechanism 70 17 conveniently comprises a rocking part or parts 22, conveniently in the form of rock shaft 23, and in wide presses, or heavy duty presses, these rocking parts, or the rock shaft 23, are preferably arranged 75 on two sides of a mid-plane of the press, in such manner as to transmit a symmetrical pressure to four or more points of connection to the blank holder slide 1. The connection between the rocking parts or 80 rock shafts and blank holder slide are conveniently in the form of toggles 25.

The rocking parts or rock shaft or shafts are preferably connected to a slide 27, which 85 slide is conveniently operated by a lever 30 fulcrumed upon the frame of the press, turning through a relatively short arc, 45° for example, and having a link connection 31, Figures 1 and 2, or 31¹, Figures 3 and 4, with said slide, and also conveniently having a link 35 connected to a reciprocating driving part, which driving part is preferably an eccentric part or pin 37, upon the driving part or gear 20 on the crank shaft 18 (which crank shaft operates the punch 95 slide).

In the embodiment of the Figures 1 and 2, the slide 27 is mounted upon the intermediate portion 10 of the frame, and preferably in the mid-plane of the press. The 100 rocking parts 22, in this embodiment, are most conveniently in the form of a rock shaft or shafts 23, symmetrically disposed with relation to the slide 27, and the slide is conveniently connected to an arm or arms 40 on the rock shaft through a link 41, the slide being thus connected to the rock shaft intermediate the ends thereof, and the connections with the slide 1. This arrangement 105 eliminates considerable torsion in the rock 110

shafts, and also provides a uniform torsion between the point of application of the driving force to the rock shaft and the points of connection of the rock shaft to the blank holder slide 1.

The lever 30 is preferably arranged substantially parallel to the blank holder or horizontal plane of the press, and conveniently extends to a point above the upper 10 face of the driving part or gear 20, thus providing for a transmission of the driving force from the outer side of the driving part or gear 20 over its periphery to the parts of the blank holder operating mechanism on 15 the press frame. Ball and socket connections 44, 45, are preferably provided between the link 35 and the lever 30, and the link 35 and the eccentric part or pin 37, in order to allow for the turning of the link 35 in two 20 planes.

The arrangement of the actuating slide 27 is preferably such that the link 41 is substantially at right angles with the line of the toggles 25, when the said toggles are extended, and the arrangement furthermore is such that, with the parts in the position just described, the eccentric part is passing through the angular positions of its movement in the vicinity of 270 degrees.

30 In Figures 3 and 4, the slide 27 is arranged upon the side piece 9 of the frame, preferably between or in a plane between the driving part or gear 20 and the said side piece 9, the side piece being provided 35 with gibbs 50 for the slide 27, and the slide being conveniently cut out or slotted in its portion which is in line with the crank shaft, as indicated at 52.

The lever 30 is preferably connected to 40 its driving part, which is preferably the gear or driving part 20, in the same manner as the lever 30 in Figures 1 and 2, viz., through a link 35 connected to an eccentric pin or part 37 along the outer side of the 45 said driving part 20. Ball and socket joints 44, 45 at the ends of the lever 35 are also provided.

The rocking parts or rock shaft or shafts 22, 23 are preferably connected at an end 50 or ends to the slide 27, the rock shaft or shafts 23, for example, conveniently extending beyond the side frame 9 of the press and being connected to the slide through an arm 54 and a link 55, pivoted on the slide 27.

55 In the case of wide or heavy duty presses, the rocking parts at each side of the press, or the two ends of a rock shaft, may be each driven by a slide 27 and operating mechanism similar to that shown in the present 60 embodiment, viz., the embodiment illustrated in Figures 3 and 4. In light duty presses, the rock shaft or shafts 27 may be driven from one end only, without objectionable torsions or strains being developed.

65 The inventive ideas herein set forth may

receive other embodiment than those herein specifically illustrated and described.

What is claimed is:—

1. A drawing press comprising a frame, a blank holder or die carrying slide, and means for reciprocating said slide with a dwell in its movement, said means comprising a shaft extending beyond said frame, a wheel and an eccentric part on said shaft beyond said frame, a lever having a relatively short angular movement and fulcrumed on said frame, and a link connected at its ends to said lever and to said eccentric part. 70

2. A drawing press comprising a frame, a blank holder or die carrying slide, and means for reciprocating said slide with a dwell in its movement, said means comprising a shaft extending beyond said frame, a wheel and an eccentric part on said shaft beyond said frame, a lever having a relatively short angular movement and fulcrumed on said frame, an actuating slide, a link connected at its ends to said lever and to said slide, and a link connected at its ends to said lever and to said eccentric part. 80

25 3. A drawing press comprising a frame, a blank holder or die carrying slide, and means for reciprocating said slide with a dwell in its movement, said means comprising a shaft extending beyond said frame, a wheel and an eccentric part on said shaft beyond said frame, a lever having a relatively short angular movement and fulcrumed on said frame, an actuating slide, a link connected at its ends to said lever and to said slide, and a link connected at its ends to said lever and to said eccentric part. 90

35 4. A drawing press comprising a frame, a blank holder or die carrying slide, and means for reciprocating said slide with a dwell in its movement, said means comprising a shaft extending beyond said frame, a wheel and an eccentric part on said shaft beyond said frame, a lever having a relatively short angular movement and fulcrumed on said frame, an actuating slide, a link connected at its ends to said lever and to said slide, and a link connected at its ends to said lever and to said eccentric part, said actuating slide being mounted 100 on said frame at a height above the lower part of said wheel, whereby the lower outer part of said frame may be free of moving parts. 105

40 5. A drawing press comprising a frame, a blank holder or die carrying slide, and means for reciprocating said slide with a dwell in its movement, said means comprising a shaft extending beyond said frame, a wheel and an eccentric part on said shaft beyond said frame, a lever having a relatively short angular movement and fulcrumed on said frame, an actuating slide, a link connected at its ends to said lever and to said slide, and a link connected at its ends to said lever and to said eccentric part. 110

45 6. A drawing press comprising a frame, a blank holder or die carrying slide, and means for reciprocating said slide with a dwell in its movement, said means comprising a shaft extending beyond said frame, 115

120

- a wheel and an eccentric part on said shaft beyond said frame, a lever having a relatively short angular movement and fulcrumed on said frame, an actuating slide, a link connected at its ends to said lever and to said slide, and a link connected at its ends to said lever and to said eccentric part, said actuating slide being mounted upon the mid-frame of the press.
- 10 6. A drawing press comprising a frame, a blank holder or die carrying slide, and means for reciprocating said slide with a dwell in its movement, said means comprising a shaft extending beyond said frame,
- 15 a wheel and an eccentric part on said shaft beyond said frame, a lever having a relatively short angular movement and fulcrumed on said frame, an actuating slide, 20 rocking parts having toggle connected at its ends to said blank holder slide, a link connecting said actuating slide and rocking parts, a link connected at its end to said lever and slide, and a link connected at its ends to said lever and said eccentric part, said 25 rocking parts being on each side of the mid-plane of said frame.

In witness whereof, I have hereunto signed my name.

WILLIAM KLOCKE.

Certificate of Correction.

It is hereby certified that in Letters Patent No. 1,468,304, granted September 18, 1923, upon the application of William Klocke, of New York, N. Y., for an improvement in "Drawing Presses," errors appear in the printed specification requiring correction as follows: Page 2, lines 119 and 120, claim 4, strike out the words "connected at its ends" and insert instead the word *connections*, and line 121, strike out the word "connecting" and insert the words *connected at its ends to*; page 3, line 19, claim 6, beginning with the word "connected" strike out all to and including the word "part", line 24, and insert the words *connections to said blank holder slide, a link connected at its ends to said actuating slide and rocking parts, a link connected at its ends to said lever and to said slide, and a link connected at its ends to said lever and to said eccentric part*; and that the said Letters Patent should be read with these corrections therein that the same may conform to the record of the case in the Patent Office.

Signed and sealed this 23d day of October, A. D., 1923.

[SEAL.]

WM. A. KINNAN,
Acting Commissioner of Patents.
